UNITED STATES PATENT OFFICE.

JOHN COLLIS, OF DES MOINES, IOWA, ASSIGNOR TO MONASH-YOUNKER COMPANY, OF CHICAGO, ILLINOIS, A CORPORATION OF ILLINOIS.

STEAM-TRAP.

No. 891,526.

Specification of Letters Patent.

Patented June 23, 1908.

Application filed September 4, 1906. Serial No. 333,089.

To all whom it may concern:

Be it known that I, JOHN COLLIS, a citizen of the United States, residing at Des Moines, in the county of Polk and State of Iowa, have 5 invented a new and useful Improvement in Steam - Traps, of which the following is a specification.

My invention relates to improvements in steam traps and is fully explained and described in this specification and shown in the accompanying drawings, in which

Figure 1 is a longitudinal section through my improved device; Fig. 2 is a horizontal section on the line 2, 2 Fig. 1 looking downwards, and Fig. 3 is a horizontal section on the line 3, 3 of Fig. 1 looking downwards.

Referring to the drawings,—A is a suitable hollow casing adapted to be connected by a union, or otherwise with a pipe a, which in practice is connected to one of the turns of a steam radiator or to such other portion of a steam carrying system as it is desired to relieve from the water of condensation and from air. This casing A is perforated at A¹, the perforation being beveled out at its upper end to provide a valve-seat a¹. Obviously when the perforation is open, as in Fig. 1, any air or water condensation within the casing A can pass out through the perforations A¹ from the system. The casing A is constricted at its upper end to form a guide for a brass or other metal tube B, which tube extends from a point slightly above the upper end of the said casing as illustrated. The casing is continued upwards by means of a tube C screwed up over the upper end of the casing A. Within the upper end of the tube C is a block B¹ centrally perforated at b and having enlarged openings at b¹ at its lower end, into which the upper end of the tube B is driven. The block B is prevented from downward movement with respect to the tube C by means of a shoulder c¹ formed in said tube.

45 The tube B is provided with a series of inwardly extending radial ribs b² which engage with, center and hold in correct alinement a pencil D of expansible material, said pencil bearing at its lower end a metal tip d adapted to coöperate with the valve seat a¹ to close the perforation A¹. This pencil has a rather snug fit between the ribs b² but is free to move with respect thereto, being prevented from extreme movement with respect thereto by

means of a spring D¹, one end of which is secured to the upper end of the pencil and the other end of which is secured to the block B¹. By means of this spring the expansible pencil D is cushioned, so that in case of extreme expansion, under heat, it will not be crushed by the undue pressure and the pencil is also drawn back to position after it has expanded, being thus held normally in the position shown in Fig. 1.

The upper end of the tube C supports an air-valve casing E, to which the contents of the casing A have access through perforations e. This air - valve casing contains a float F, beneath which is a vertical tube G having inwardly extending radial ribs g, and ribs B, and an expansible pencil H lying within this tube. By this arrangement an influx of the water will raise the float F, while an influx of steam will raise the temperature of the expansible pencil H to the end that the float is also raised. The float F carries, at its upper end, a valve point F¹ that will coöperate with a valve seat a², situated in the upper end of the air-valve casing E. An opening from the air-valve chamber E extends upward into a diaphragm chamber I, the upper surface of which is formed by a flexible diaphragm I¹, having a central perforation and valve seat i. Within the diaphragm chamber is a double tipped valve-fitting J, which normally closes the opening from the air-valve casing E and which closes the opening i when, for any reason, the diaphragm is drawn down. The diaphragm is protected from injury by means of a flat cover K having a central perforation k for the escape of gas.

At the lower end of the casing A is mounted a check-valve fitting L, in which is supported a valve l which is normally held upwards by means of a very light spring l¹.

The operation of my improved device is substantially as follows: With a return pipe gravity system the lower end of the casing is connected with the return pipe and the steam, air and water of condensation pass in through the nipple a. When the system is first started after a long period of disuse, the water and air in the radiators alone enter the device for a considerable period, these substances sometimes entering together and sometimes in succession. The air upon entering the device will rise and eventually

pass out of the small opening at the top, the valves being open. The water of condensation upon entering will flow out at the bottom through the return pipes. In case 5 water should enter the device at any time in quantity beyond the capacity of the opening at the lower end thereof, it is prevented from flowing from the top by means of the float which will raise and close the valve, holding 10 the water within the device until it has time to flow out at the bottom in the proper way. Upon the entrance of steam to the device the expansible pencils are heated and expand, and thereupon the opening at the lower end 15 of the casing A and the opening at the upper end of the air valve casing E are closed, thus preventing the escape of any steam whatever.

Upon the cooling of the pipes of the system, such as occurs at night when the fire is 20 banked, the condensation of the steam causes a partial vacuum, the effect of which is to draw down the valve J and to draw up the valve l , thus maintaining the vacuum continuously. The opening in the diaphragm 25 I^1 is very small and in case of any considerable leakage around the lower end of the valve fitting J the diaphragm will be drawn down, thus insuring a double obstruction between the atmosphere and the pressure 30 vacuum in the heating system. This maintenance of the pressure vacuum insures a continued production of steam, even though the temperature of the water in the boiler falls considerably below the boiling point of 35 water at atmospheric pressure. The diaphragm is prevented from distortion by ribs r^1 with which it contacts. A further advantage arises by reason of the fact that when the steam is cut off from the radiator, to 40 which my improved device is applied, the vacuum which is instantly formed by the condensation of the steam, is preserved by means of the valves described, so as to prevent not only the entrance of air to the radiator for a considerable period of time, but to 45 prevent any water of condensation in the return pipe from being sucked back into the radiator as often happens. Thus when steam is readmitted the unpleasant hammering noise is to a large extent eliminated. Furthermore, with my improved device the 50 steam has free access at all times to the expansible pencils so as to produce the maximum expansion in the minimum time, and 55 at the same time the pencils are prevented from buckling by means of ribs b^2 and g . Furthermore, the pencils can be removed at any time by removing the tubes in which

they are supported and pushing them or pulling them from place.

In case it is desired to use my improved device on a vacuum system supplied with a pump, the air-valve, obviously, becomes unnecessary and can be removed, the top of the tube C being closed by a tight cap.

What I regard as new and desire to secure by Letters Patent is,

1. In a steam trap, a tube having inwardly projecting ribs, an expansible pencil centered and held in position by said ribs, and an exhaust valve adapted to be closed by the expansion of said pencil.

2. In a steam trap, a casing having an exhaust opening, a tube mounted within the same having inwardly extending ribs, an expansible pencil centered and held in place between said ribs and a suitable tip movable by the expansion of said pencil to close the exhaust opening in the casing.

3. The combination with a casing having a perforation at its lower end, of an expansible device adapted to control said perforation, an air valve chamber above said casing and having communication therewith, a passage leading from said chamber to the atmosphere, a valve controlling said passage, and thermostatically and float-operated means for closing said valve.

4. The combination with a casing having a perforation at its lower end, of an expansible device adapted to control said perforation, an air valve chamber above said casing and having communication therewith, a passage leading from said chamber to the atmosphere, a valve controlling said passage, thermostatically and float-operated means for closing said valve, and devices for preventing the return of fluid to the air-valve or through the lower perforation of the trap.

5. In a device of the class described, the combination with a casing having a perforation leading therefrom, float and thermostatically-controlled means for closing said perforation, a valve adapted to prevent the return of vapor through said perforations to the casing, a diaphragm beyond said valve provided with a suitable perforation adapted to coöperate with the valve and become closed thereby when the diaphragm is retracted, and a series of ribs adapted to support and prevent the distortion of the diaphragm when retracted.

JOHN COLLIS.
